(57) **CLAIM**

The ornamental design for a cover for earphone case or the like, as shown and described.

DESCRIPTION

FIG. 1 is a front, top, and right-side perspective view of a cover for earphone case or the like, showing my design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a back, top, and right-side perspective view thereof; and,

FIG. 9 is a front, bottom, and right-side perspective view thereof.

The broken lines shown in FIG. 3 depict interior parts of the cover for earphone case or the like, which form no part of the claimed design. The interior parts of the cover for earphone case or the like, seen through openings in FIGS. 3 and 8, form no part of the claimed design.

1 Claim, 7 Drawing Sheets
